SCREW DRIVER

Louis Balga, Bridgeport, Conn.

Application July 19, 1935, Serial No. 32,283

1 Claim. (Cl. 279—89)

This invention relates to certain new and useful improvements in screw drivers.

The primary object of the invention is to provide a screw driver of the side or lateral type embodying an elongated handle and shaft with a relatively short shaft extending at an angle to the aforesaid shaft with gear connections therebetween comprising bevel gears cut directly into the adjacent ends of the two shafts.

10 A further object of the invention is to provide a screw driver of the foregoing character wherein in the outer end of the short shaft has a dovetailed cross-slot therein for the reception of a similarly shaped inner end of a screw driver blade 15 with a tensioned locking ring slideable on the short shaft for retaining the blade in position therein.

With the above and other objects in view that will become apparent as the nature of the invention is better understood, the same consists 20 in the novel form, combination and arrangement of parts hereinafter more fully described, shown in the accompanying drawing and claimed.

25 In the drawing:—

Figure 1 is a front elevational view of a screw driver constructed in accordance with the present invention;

Figure 2 is a longitudinal sectional view taken 30 on line 2—2 of Figure 1, showing the direct gear drive between adjacent ends of the two shafts and the removable screw driver blade retained in engagement with one shaft by a tensioned locking ring;

Figure 3 is a fragmentary side elevational view, 35 partly in section showing the tensioned locking ring retracted to uncover the cross slot in the shaft end with the screw driver blade removed;

Figure 4 is a perspective view of a short screw 40 driver blade; and

Figure 5 is a perspective view of a relatively long screw driver blade, both blades having their inner ends fashioned for sliding interlocking engagement with the supporting shaft.

45 The screw driver embodies an elongated casing 10 having an elbow formation 11 at one end providing a relatively short right angularly extending casing section 12, the two casings 10 and 12 rotatably supporting the drive or operating shafts for a screw driver blade.

An elongated shaft 13 is journalled in the casing section 10 and is restrained from longitudinal movement therein by the screw 14 threaded through the casing section 10 with the inner end thereof entering an annular groove 15 formed

in the shaft 13. A relatively short shaft 16 is journalled in the angularly extending casing section 12 and projects therefrom as at 16a, the shaft 16 being restrained from longitudinal movement by means of the screw 17 threaded through the side wall of the casing section 12 and entering an annular groove 18 in the shaft 16. The adjacent ends of the shafts 13 and 16 are intermeshed as at 19 and 20 respectively by means of bevel gear formations being cut directly in the adjacent shaft ends, this arrangement eliminating separate gear devices.

A hand grip 21 encloses the inner ends of the casing section 10 and is suitably anchored thereto, the elongated shaft 13 projecting outwardly 15 of the casing section 10 and hand grip 21 to accommodate the mounting thereon of an operating handle 22 that is locked thereto by means of the cross pin 23. It will be understood that the hand grip is engaged by one hand of the 20 operator and the other hand of the operator employed for rotating the handle 22 to impart rotation to the elongated shaft 13 and to the shaft 16 by means of the gear connections 19 and 20 between the two shafts.

As shown more clearly in Figures 2 and 3, the outer ends of the short shaft extension 16a is flared outwardly to provide an abutment collar 24 and said shaft extension at its outer end is provided with a transversely extending dove-tailed shaped groove 25. A relatively short screw driver blade 26 is of wedge-shape as shown in Figures 2 and 4 and is adapted to be transversely slid into the groove 25 when the latter is exposed as shown in Figure 3 for interlocking engagement with the shaft extension 16a. To retain the screw driver blade 26 in position, a ring 27 is freely mounted on the shaft extension 16a and has an annularly recessed forward side 28 that is moved into engagement with the abutment collar 24 with the ring closing the ends of the slot 25. A coil spring 29 surrounds the shaft extension 16a between the outer end of the shaft section 12 and ring 27 for normally influencing the ring in a direction of movement toward the outer end of the shaft extension and into the position shown in Figure 2. To remove the screw driver blade 26 from the shaft 16, the ring 27 is moved over the shaft extension 16a against the tension of the spring 29 to expose the ends of the cross slots 25 and at which time the screw driver blade 26 may be easily removed from the shaft.

An elongated screw driver blade is illustrated in Figure 5 and comprises a shank 30 having a 55

tapered screw engaging end 31 with the inner end thereof reduced and flattened to provide a key portion 32 of wedge-shape for reception in the cross groove 25 in the shaft extension 16a.

5 While the invention has been herein referred to as a screw driver, it is to be understood that the principle of operation may be embodied in other tools, such as augers and in which blades are removably mounted.

10 From the above detailed description of the invention, it is believed that the construction and operation thereof will at once be apparent and while there is herein shown and described the preferred embodiment of the invention, it is nevertheless to be understood that minor changes

15 may be made therein without departing from the spirit and scope of the invention as claimed.

I claim:—

In a detachable blade mounting for screw driv-

ers, a casing section, a shaft journalled in the casing section and projecting from one end thereof, the projecting end of the shaft having a transversely extending key slot in the outer end thereof, an outwardly flaring abutment shoulder at the outer terminal end of the shaft, a key-ended screw driver blade removably positioned in the slot, a ring surrounding the projecting end of the shaft and having a tapered inner wall for mating contact with the flared collar on the shaft 10 with the outer side of the ring flush with the end of the shaft at its limit of movement towards the end of the shaft, and a coil spring surrounding the shaft and engaged with the adjacent end of the casing and ring for normally forcing the latter towards the outer end of the shaft to close opposite ends of the slot and retain the screw driver blade therein. 5

LOUIS BALGA.
